Inventor:
FRANK D. LORTON,

By
John H. Bunning,
his Attorney.

UNITED STATES PATENT OFFICE.

FRANK D. LORTON, OF ST. LOUIS, MISSOURI, ASSIGNOR TO EMIL NATHAN, TRUSTEE.

CAMP-FIRE OUTFIT.

Application filed November 22, 1921. Serial No. 517,080.

This invention relates to a device for supporting the various vessels, etc. used in cooking over a campfire.

- One of the objects of this invention is to 5 provide a device of this character which can be readily set up so as to support the various utensils and articles over a campfire, but which can be disassembled to enable it to be packed in a small space.
- 10 Another object is to provide a device of this character which is simple in its construction, effective in its action and economical to manufacture.

Further objects will appear from the detailed description taken in connection with the accompanying drawing, in which:

Figure 1 is a perspective view of a device embodying this invention;

Figure 2 is a detail longitudinal vertical section; and

Figure 3 is an enlarged section on line 3—3, Figure 1, showing the parts in elevation.

Referring to the accompanying drawing, 25 the device comprises a stake 1 having a sharpened point adapted for insertion into the ground. This stake is provided with a pair of pedals 2 projecting therefrom whereby it may be forced into the ground by foot 30 pressure. A shank 3 projects upwardly from the stake above the pedals and this shank is fluted as shown in Figure 3, and as it is reduced in diameter, provides shoulders 4. A standard 5 formed of a piece of 35 pipe fits loosely over the projecting end or shank 3 formed on the stake and is arranged to rest on the shoulders 4. This standard may be provided with a cap 6 which may be integral therewith or may be provided with 40 a shank 7 driven into the hollow standard. By providing a fluted shank 3, a good bearing will be provided between the standard and the stake which will not become clogged or tight by the presence of rust, water or 45 foreign matter.

A series of racks 8, 9 and 10 are each provided with a shank 11 having an eye arranged to take loosely over the standard. The shank 11 is turned upwardly at its end 50 as shown to provide standard-engaging walls 12 and 13 which are out of alinement, the inner wall 12 being higher on the standard than the outer wall 13, and the wall 13 being short as shown in Figure 2. Accord-

ingly, when any of these racks is placed 55 over the standard, the free end will tend to swing the rack about a horizontal line between the walls 12 and 13 as an axis, thereby causing the wall 12 to bind against the standard and causing the wall 13 to bite into 60 the standard so as to hold it in position; while, therefore, any rack may be moved up and down by raising the free end thereof so as to cause the unclamping to take place and while it may be rotated to any position 65 on the standard, as soon as it is released, it will bind on the standard and will be positively held in position. The greater the weight, on the rack, the more tightly will 70 it bind. The racks may, therefore, be positioned in various relations on the standard and as the standard is mounted for free rotation on the stake, the racks may be selectively positioned over the campfire on the ground. These racks may be of various 75 forms, thus, rack 8 may be an arm to hold a kettle or a pot, the rack 9 may be a loop to hold a frying pan, while the rack 10 may be a grid for broiling.

It will, therefore, be seen that the invention accomplishes its objects. A simple campfire outfit is provided which can be readily set up and disassembled. When set up, it will conveniently support the various utensils, etc. used in camping over a campfire built on the ground. When disassembled, it can be packed in a small box so as to be readily transportable.

It is obvious that various changes may be made in details of construction without departing from the spirit of this invention; it is, therefore, to be understood that this invention is not to be limited to the specific details shown and described.

Having thus described the invention, what 95 is claimed is:

A campfire outfit, comprising, a supporting stake having a blade adapted to be forced into the ground, a pedal for forcing the same, and a fluted shank above said 100 pedal and terminating in a shoulder, a standard fitting freely but snugly over said shank to be supported on said shoulder, and racks adjustably mounted on said standard.

In testimony whereof I affix my signature 105 this 22nd day of September, 1921.

FRANK D. LORTON.
